UNITED STATES PATENT OFFICE.

GEORGE T. BYNNER, OF CHICAGO, ILLINOIS.

DESIGN FOR AN EMBLEM, BADGE, OR ARTICLES OF A SIMILAR NATURE.

52,469.

Specification for Design.

Patented Sept. 24, 1918.

Application filed February 25, 1918. Serial No. 219,143. Term of patent 7 years.

To all whom it may concern:

Be it known that I, GEORGE T. BYNNER, a citizen of the United States, residing at Chicago, in the county of Cook and State of Illinois, have invented a new, original, and ornamental Design for Emblems, Badges, or Articles of a Similar Nature, of which the following is a specification, reference being had to the accompanying drawing, forming part thereof.

In the drawing Figure 1 is a plan view of a badge showing my new design; Fig. 2 is a cross-section on the line 2—2 of Fig. 1.

I claim:

The ornamental design for an emblem, badge, or articles of a similar nature, as shown.

GEORGE T. BYNNER.
